UNITED STATES PATENT OFFICE

FRED BENJAMIN MONAR, OF WASHINGTON, DISTRICT OF COLUMBIA

COMMUNICATION SYSTEM

Application filed May 15, 1928. Serial No. 277,930.

(GRANTED UNDER THE ACT OF MARCH 3, 1883, AS AMENDED APRIL 30, 1928; 370 O. G. 757)

My invention relates broadly to communication systems and more particularly to a system of intercommunication between a plurality of stations, for example, between 5 the different members of the crew of an aircraft.

The object of my invention is to provide a reliable system of intercommunication, which will retain its reliability in spite of 10 external noises of great volume.

A further object of my invention is to provide an intercommunication system which is an integral part of the radio receiving system of an aircraft, thus doing away with the 15 necessity for the extra batteries, transformers and switching devices required when a separate intercommunication system is employed as heretofore. The saving of weight thus accomplished is, of itself, a great advantage over the intercommunication systems heretofore used.

Further objects of my invention will appear more fully hereinafter as the description of the method and apparatus is developed.

My invention consists substantially in the construction, combination and arrangement of parts associated therewith or as will be more fully hereinafter set forth as shown by 30 the accompanying drawing and finally pointed out in the appended claims.

The drawing forming a part of this specification represents a circuit embodying my invention. The vacuum tube 1 is of the ordinary three electrode type, which may be one of the tubes of the radio receiving set of an aircraft; that is, if an aircraft has a radio receiving set, one of the tubes of said set may be associated with the circuit of my invention without interfering with the normal function of said tube in said receiving set. For purposes of this description I have shown the tube as the detector tube of a receiving set connected as an oscillator of the 40 autodyne type, as in this manner oral intercommunication may with special ease be reliably effected as hereafter described. Pursuant to this preferred form of disclosure I have shown the grid 10, grid leak 2 and its 45 associated condenser 3. The variable con-

denser 4 and the inductance 5 form a tuned circuit 18 the function of which will be more fully explained later. The tickler coil 6 is inductively associated with the inductance 5, and is in series with the plate 7, the telephone 8 (of which there may be a plurality as indicated at 8'), and the source of plate potential 9. The filament 11 is fed from the filament-battery 12. The amount of filament current may be regulated by the rheostat 13.

Across the filament battery 12 is connected a circuit 17 comprising the inductance 14, the microphone transmitter 15 and the switch 16. There may be a plurality of microphones and switches as indicated at 15' and 16'. The inductance 14 is in inductive relation with the inductance 5. The switches 16 and 16' are closed when the intercommunication system is in use. When opened they prevent the filament-battery 12 from becoming discharged, hence the normal position of the switches 16 and 16' is open when the intercommunicating system is not in use.

The operation of my invention is as follows: The switch 16 or 16' being closed, the current flowing in the circuit 17 is varied in the usual manner by the microphone 15 or 15'. Due to the inductive relation between the inductance 14 and the inductance 5 a variation of current in the former will induce an E. M. F. in the latter, which in turn will cause a corresponding variation of potential of the grid 10. By the action of the tube 1 these variations of grid potential result in audible signals in the telephones 8 or 8'.

This is the general operation of my invention, and is sufficient to give clear and distinct communication under normal conditions. Conditions may arise however where it may be necessary to greatly increase the volume of the signal in the communication system of my invention. As an example, the noise of an aircraft motor has heretofore made intercommunication between members of the aircraft's crew either impossible or extremely unreliable. With my invention such communication becomes reliable and easily effected.

To obtain successful operation under adverse conditions of the type described I have

provided the variable condenser 4 as a means for tuning the circuit 18 though any other means such as varying the inductance 5 would be suitable. By tuning the circuit 18 and by 5 operating the tickler coil 6, the tube 1 may be caused to oscillate and the frequency of the oscillations controlled. With the tube in an oscillating condition the voltage across the condenser 4 which is impressed upon the grid 10 is large in magnitude compared to such voltage when the tube is not oscillating for in the latter case it is only the voltage induced in the inductance 5 as above described.

When the impedance of the circuit 18 is 15 changed by a change in the impedance of the adjacent circuit 17 the voltage impressed on the grid 10 of the oscillating tube 1 undergoes relatively large variations proportionate to the variations of impedance in the circuit 20 17, and thus the signal to be transmitted is reproduced with large volume and intensity in the telephones 8 and 8'.

It will be understood that while the tube 1 may be a tube of the regular radio receiving 25 set employed, the circuits of my invention associated with this tube may be separated from the circuits of the receiving set associated with the same tube. Furthermore, in place of the telephones 8 and 8' there may 30 be one or more stages of amplification, and wherever a telephone is employed a loud speaker may be substituted.

Further objects of my invention are now 35 apparent. For instance, a member of an aircraft's crew wearing the telephones 8 and 8' may receive signals from a distant station and yet be in instant communication with other members of the aircraft's crew. If external noises are excessive the tube 1 may 40 readily be put into the oscillating state thereby making intercommunication.

It will be understood that the above description and accompanying drawing comprehend only the general and preferred embodiment of my invention and that minor detail changes in the construction and arrangement of parts may be made within the scope of the appended claims without sacrificing any of the advantages of my invention.

50 The invention herein described may be manufactured and used by or for the Government of the United States for governmental purposes without the payment to me of any royalty thereon or therefor.

55 Having thus described my invention what I claim is:—

1. In a combined oscillating detector radio receiving and local voice intercommunication system, a vacuum tube having input and 60 output circuits, variable impedance means associated with said input circuit, means in said output circuit inductively associated with said variable impedance means whereby said vacuum tube is placed in an oscillating state, which aforesaid elements are a part of

the oscillating detector radio receiving system, in combination with an impedance circuit the impedance of which may be independently varied at a predetermined point 70 said point lying outside the physical limits of said receiving system, means whereby a variation in the impedance of said impedance circuit will produce a variation in the impedance of said impedance means associated with said input circuit, whereby radio signals 75 may be observed as well as local intercommunication voice frequencies.

2. In a combined oscillating detector radio receiving and local voice intercommunication system, a vacuum tube having input and 80 output circuits, variable impedance means associated with said input circuit, means in said output circuit inductively associated with said variable impedance means whereby said vacuum tube is placed in an oscillating state, which aforesaid elements are a part of the oscillating detector radio receiving system, an impedance circuit the impedance of which may be independently varied at a plurality of independent points said points lying outside the physical limits of said receiving system, means whereby a variation in the impedance of said impedance circuit will produce a variation of said impedance means associated with said input circuit, whereby locally generated voice frequencies may be observed in a plurality of telephone receivers in the output circuit of said receiving system.

3. In a combined oscillating detector radio receiving and local voice intercommunication system a vacuum tube having grid filament and plate electrodes, variable impedance means associated with said grid electrode, means associated with said plate electrode and inductively associated with said variable impedance means whereby said tube is placed in an oscillating state and a source of electrical energy for said filament electrode, which aforesaid elements constitute a part of an autodyne receiving system, in combination with a circuit connected across said source of electrical energy said circuit including a coil and a microphone, said coil being inductively associated with said variable impedance means whereby radio as well as intercommunication voice frequencies may be observed.

4. In a combined oscillating detector radio and local voice communication system a vacuum tube having grid filament and plate electrodes, variable impedance means associated with said grid electrode, means associated with said plate electrode and inductively associated with said variable impedance means whereby said tube is placed in an oscillating state and a source of electrical energy for said filament electrode, which aforesaid elements constitute a part of an oscillating detector radio receiving system, in combination with a circuit connected 120

across said source of electrical energy said circuit including a coil and a plurality of microphones, said coil being inductively associated with said variable impedance means 5 whereby radio as well as intercommunication voice frequencies may be observed.

5. In an intercommunication system, the combination of a vacuum tube having a grid-filament circuit consisting of a grid leak and 10 condenser and a tuned circuit, a plurality of microphones in a circuit inductively coupled to said tuned circuit, whereby the impedance of said tuned circuit is caused to vary according 15 to voice frequencies impressed upon any of said microphones; a plate-filament circuit consisting of a source of power, a plurality of telephone receivers corresponding in number to said microphones and respectively located adjacent thereto and a regenerative inductance which is coupled to said tuned circuit, whereby said vacuum tube is caused to oscillate at a frequency determined by said tuned circuit and the voice frequencies impressed upon said microphones are greatly 20 amplified and observed in said telephone receivers, in said plate-filament circuit.

6. The method of intercommunication in an area, provided with an oscillating detector radio receiving system having a radio detector input circuit for external radio reception, including the steps of varying the impedance of said circuit according to local 30 voice frequencies and receiving on said system said radio and intercommunication voice 35 frequencies.

7. The method of intercommunication in an area subject to external noises of great volume, said area being provided with an oscillating detector radio receiving system 40 having a radio detector input circuit for external communication, including the steps of tuning said receiving system to a frequency on which no radio signals are heard and varying the impedance of said detector 45 input circuit according to local voice frequencies and receiving on said system the said intercommunication voice frequencies.

8. The method of intercommunication in an airplane provided with an oscillating detector radio receiving system, having a radio detector input circuit for external communication, including the steps of energizing a microphone circuit by the regular filament battery associated with said detector circuit, 50 said microphone circuit being inductively coupled to said detector input circuit, varying the impedance of said detector input circuit by varying the current flowing in said microphone circuit according to local voice 55 frequencies, and receiving on said system 60 said intercommunication voice frequencies.

FRED BENJAMIN MONAR.
